PAPER MAKING

Filed Aug. 1, 1924

UNITED STATES PATENT OFFICE.

CHARLES A. TIFFT, OF HOLYOKE, MASSACHUSETTS.

PAPER MAKING.

Application filed August 1, 1924. Serial No. 729,642.

Heretofore it has been customary in certain paper mills to use what is known as a Jordan between the machine chest and the paper-making machine so that the Jordan is continuously treating just the amount of stock that the paper-making machine is using. Furthermore it has been necessary to control the amount of stock passing to the machine and this has invariably been done by means of a gate controlling the amount of stock passing into the Jordan; that is, the stock was controlled prior to its passing into the Jordan and not subsequent thereto. This method of operation permitted the stock, as soon as it passed through the gate, to flow on through the Jordan to the paper-making machine there being little tendency for it to accumulate in the Jordan. To have the Jordan properly treat this material it has been necessary to use a considerable amount of water and to set the knives of the Jordan rather closely. This causes a rapid wearing of the knives and also there is considerable cutting of the pulp fibre both of which are undesirable.

It has long been recognized that it was desirable to have the Jordan full of stock or as full as possible and one common method of attempting to accomplish this was as follows. An adjustable dam was installed where the stock was flowing away from the Jordan. This consisted of a box with an overflow which could be made higher or lower by using more boards or fewer boards. This would hold back the material in the Jordan to a certain extent and tend to lessen some of the undesirable features mentioned above. However this method did not fully accomplish the desired results even though it helped some. Another feature of the dam method and perhaps the most undesirable one was that the stock seemed to be held back and then it would be suddenly released flooding the paper-making machine with an excess of stock. This gave a paper greatly lacking in uniformity. It is not necessary for the purposes of this specification to set forth the precise theory underlying this spasmodic action of the dam method. It may possibly be due to the pocketing of the material behind the dam and then its sudden discharge when sufficient material has accumulated behind it to force it over.

My invention overcomes the defects enumerated above. Broadly it is a combination and method of operating a Jordan full of stock. My method fills up the Jordan completely and even places a head of ten feet or more on the stock in the Jordan. It also places the means for controlling the flow of stock on the outlet side of the Jordan where this pressure exists. The dam method operating on an old and entirely different principle used a head of not more than two or three feet and would not be at all adapted to such a head as my method gives. Also less water is necessary to give the proper treatment in the Jordan. It is not necessary to adjust the knives as closely. Also the result of a readjustment of the setting of the gate is not so slow to become effective on the paper-making machine as in the former practice where a considerable amount of material accumulated between the gate and the machine.

As already stated, this method of having the Jordan full makes it unnecessary to adjust the knives so closely. The resultant action in the Jordan seems to have less cutting but more of a drawing out of the fibre similar to the action in the beaters. This is called hydrating and produces a superior quality of stock. One advantage is that formerly the knives wore very rapidly and every two or three months it was necessary to go through the chipping operation or to put in a new set of knives, whereas they will now go nine months to a year. Also the paper is stronger and more homogeneous. I have found this method to increase the Mullen tester reading by ten or fifteen percent on heavy paper such as 44-pound cover paper and even fifty percent on light weight bond or tissue paper. Furthermore this is done with a reduction of the time the stock spends in the beater by as high as forty percent. Thus the beater capacity for a given run of paper is reduced at the same time as the quality is being improved. Also the spasmodic action of the dam method is entirely absent in my method. There are also other advantages but the above appear at present to be the most important ones.

My invention is capable of a variety of expressions and I do not wish to confine myself to the specific form herein described. So far as my experiments with an entirely

new method have indicated, the preferred embodiment of my invention is shown in the accompanying drawing wherein

Fig. 1 shows schematically one arrangement of parts suitable for carrying out my invention.

1 is the machine chest from which the pulp or paper stock is being continually taken to the paper-making machine. 2 is 10 the pipe through which the stock is carried and 3 is a stuff pump to force the stock into the Jordan box 4. The capacity of the stuff pump 3 is such that it will always supply more stock than is actually required by the 15 paper-making machine. This excess stock fills up the Jordan box 4 until it is higher than the overflow barrier 5 and the excess flows to the left and back to the machine chest through pipe 6. The stock for the 20 paper-making machine passes through the pipe 7 into the Jordan 8 and then through the pipe 9 to the gate which is shown at 10. The gate 10 is adjustable so that the amount of stock that passes through and to the 25 paper-making machine 12 or its save-all box 11 may be changed from time to time as the weight of the paper may require. I prefer to carry the pipe 9 in a more or less uniform pitch from the Jordan 8 to the gate 10. 30 Just how far this condition could be varied without materially affecting the result I do not know but if sharp turns were introduced so as to produce pockets some of the disadvantages of the dam method of control 35 would ensue.

The operation is as follows. The course the stock follows has already been indicated. The gate 10 is set to permit the proper amount of stock to pass on toward the paper-making machine. Inasmuch as the stuff pump 3 is supplying more stock than the paper-making machine requires, the stock will fill up the pipe 9, Jordan 8, pipe 7, and finally the Jordan box 4 until the overflow 45 pipe 6 is taking all the excess back to the machine chest 1. By this means the Jordan is always operating full of stock and under a head or pressure. It is possible to set the knives of the Jordan less closely and to use 50 less water. I have found that this gives more of a beater action and less of a cutting action to the paper stock. The numerous advantages derived thereby have already been set forth and will not be repeated.

To elucidate more fully the former practice and wherein it differed from my method the position of the gate according to the former practice has been indicated at 13. By adjusting this gate at 13 the proper amount 60 of material would pass on toward the paper-making machine and therefore the same excess would return to the machine chest 1 by way of the pipe 6. By this arrangement, however, the Jordan would not be more than half full of material. It would be necessary

to set the knives closer with consequently greater wear and less desirable results generally as already set forth. Also the amount of stock passing to the paper-making machine could not be changed so promptly 70 because the gate 13 was considerably farther from the paper-making machine than is the gate 10.

But even more valuable than the results in the Jordan itself is the greater uniformity 75 of the stock flowing to the paper-making machine and consequent greater uniformity in the paper. The precise reason for this is not at present understood. One theory already mentioned is that the use of a dam 80 permits pocketing of the material and then its sudden release. Another theory is as follows. When the gate is on the inlet side of the Jordan it makes no difference whether the stock is thick or thin in the amount of 85 stock that passes through the Jordan for the latter will treat and pass on whatever comes to it. But with the gate on the outlet side and the pressure backed up through the Jordan the amount of stock that passes 90 through will depend somewhat on the density. In other words if it is thick the Jordan will only be able to treat a somewhat smaller quantity and the thicker stock which would otherwise make a heavier sheet of paper is 95 somewhat compensated for by the fact that a less quantity passes on to the machine per unit time. But whatever may be the true theory of operation there is no doubt but that the paper is far more uniform than with 100 the gate at the inlet side of the Jordan.

Another very important advantage is the elimination of stuff-gate plugging. In the old method with the gate at 13 and very little head behind it, if only required a small 105 amount of uncleared stock to stop the flow entirely to the Jordan which in turn would result in the paper web leaving the wire. With the gate at 10 this trouble has been entirely eliminated. Any such uncleared 110 stock is completely hydrated before it reaches the gate.

I claim:

1. In paper-mill machinery, the combination of a Jordan, a paper-making machine, 115 a pipe discharging directly from the Jordan to the paper-making machine, said pipe being carried in a uniform pitch, and a gate controlling the flow in said pipe.

2. In paper-mill machinery, the combination of a paper-making machine, a Jordan, connections through which the paper stock flows directly from said Jordan to said machine, and means in said connections whereby a head is maintained on the stock in the 120 Jordan in excess of the elevation of any portion of said connections.

3. In paper-mill machinery, the combination of a paper-making machine, a Jordan, connections through which the paper stock 130

- flows directly from said Jordan to said machine, and a gate in said connections for simultaneously regulating the quantity of stock delivered to said machine and maintaining a head on the stock in the Jordan.
4. In paper-mill machinery, the combination of a paper-making machine, a Jordan, a closed passage through which the paper stock flows from said Jordan directly to said machine, and means in said passage for constricting the same to regulate the flow of stock and maintain a pressure on the stock.
5. In the manufacture of paper, the method which consists in passing the paper stock through a Jordan, maintaining the stock in said Jordan under a relatively high head, passing the stock directly to a paper-making machine, and regulating the quantity of stock flowing from the Jordan to the paper-making machine to maintain relatively high pressure on the stock in the Jordan.
6. In the manufacture of paper, the method which consists in passing the paper stock through a Jordan, passing the stock from the Jordan directly to a paper-making machine through a closed passage, and constricting the passage from said Jordan to said machine to regulate the quantity of stock delivered to said machine.
7. In the manufacture of paper wherein a Jordan delivers directly to the paper-making machine, the step of controlling the flow of stock to the paper-making machine at the outlet side of the Jordan.
8. In the manufacture of paper wherein a Jordan delivers directly to the paper-making machine, the step of controlling the flow of stock between the Jordan and the paper-making machine where the stock is under a pressure by reason of said control.
9. In combination, a Jordan, a paper-making machine, a Jordan box located at a higher level than the Jordan, means for feeding stock to the Jordan box at a faster rate than required by the paper-making machine, an overflow in said Jordan box, a closed conduit from said Jordan box to said Jordan, a second closed conduit from said Jordan to said paper-making machine, and means in said second conduit for controlling the rate at which stock is fed to the paper-making machine.
10. In paper-mill machinery, the combination of a Jordan, a paper-making machine, a pipe passing continuously downward from a feed point above said Jordan to said Jordan and continuously downward from said Jordan to said paper-making machine, and means in said pipe at said paper-making machine for simultaneously controlling the flow of stock and maintaining a head on the stock in said Jordan.

In testimony whereof I affix my signature.
CHARLES A. TIFFET.
